His Attorney.

UNITED STATES PATENT OFFICE.

EDWARD A. WAGNER, OF FORT WAYNE, INDIANA, ASSIGNOR TO GENERAL ELECTRIC COMPANY, A CORPORATION OF NEW YORK.

X-RAY TERMINAL.

Application filed September 23, 1921. Serial No. 502,700.

To all whom it may concern:

Be it known that I, EDWARD A. WAGNER, a citizen of the United States, residing at Fort Wayne, county of Allen, State of Indiana, have invented certain new and useful Improvements in X-Ray Terminals, of which the following is a specification.

My invention relates to terminals for electrical apparatus and is more particularly concerned with terminals adapted for use with transformers designed for X-ray service.

The general object of my invention is the provision of a terminal of this nature which shall be as simple in construction as is consistent with efficiency in operation and in which the different parts may be easily assembled and disassembled so that parts which may be found to have defects during the process of manufacture and test or while in use may be discarded and replaced without discarding the entire terminal.

One embodiment of my invention is illustrated in the accompanying drawing in which Fig. 1 shows an X-ray transformer equipped with a terminal constructed in accordance with my invention; Fig. 2 shows a longitudinal sectional view of one of the terminals; Fig. 3 is a view of the sphere at the upper end of the terminal looking in the direction of the arrow A of Fig. 2; Fig. 4 is a side view of the sphere with a portion broken away on the line B of Fig. 3 and looking in the direction of the arrow; and Fig. 5 is a longitudinal sectional view of the socket shown in Fig. 2.

In the embodiment of the invention shown in the drawing, the terminal includes a hollow tubular stem portion 1 formed with a longitudinal opening to accommodate the conductor elements of the terminal. Built into the lower end of the stem 1 is a metal sleeve 2 which forms a metallic lining for the stem. The stem 1 is formed of some suitable insulating material such as the phenol condensation product known as bakelite which may be moulded around the sleeve 2 so that both are securely and permanently united. A flange 3 is formed on the stem 1 which is secured to the top or cover 4 of the transformer by a nut 5, a gasket 6 being provided under the flange 3.

The metallic sphere 7 fits against the concave upper end of the stem 1 and is formed with a hub 8 having a pair of projections 9 which fit into corresponding recesses in the stem to prevent relative rotation between the stem and sphere after the two are secured together. The sphere may be cast or spun in two halves which are fitted and welded together to form a unit. In a small flat surface formed on the sphere one or two holes are made to receive sockets. It is common in X-ray transformers to provide one terminal carrying a single conductor and a second terminal carrying two conductors so that one terminal, such as the terminal 11 shown in Fig. 1, would have a single socket and the other terminal would have two sockets as shown most clearly in Fig. 3. The terminal illustrated in detail in the drawing is constructed with two sockets. Flexible conductors ending in plugs which fit these sockets may be used to connect the terminal conductors to other apparatus. A sleeve 12 of conducting material is threaded into the hub 8 of the sphere and fits into the sleeve 2 as far as or slightly beyond its lower end. Inside the sleeve 12 is a rod 13 of conductive material held in place and insulated from the sleeve by insulating bushings 14 and 15 and some suitable insulating cement 16. Two sockets 17 and 18 are screw-threaded into the sphere 7, the socket 18 being insulated from the sleeve by a bushing 19. A connecting link 20 joins the socket 18 and the rod 13. Clips 21 and 22 are provided for connecting transformer leads to the rod 13 and sleeve 12 respectively.

During the process of manufacture, the terminal is first assembled in two units, one of these units including the stem 1 and the sleeve 2 and the other unit including the sphere 7, the sleeve 12 and the parts enclosed within this sphere and sleeve. These two units are then slid together until the sphere fits against the concave upper end of the stem 1 and the lower end of the sleeve 2 is secured by solder 23 all around to the sleeve 12, making the joint between them oil-tight.

In the complete two conductor terminals just described, the path of the current from one of the transformer leads is through the clip 22, sleeves 2 and 12, sphere 7 and

socket 17 and from the other transformer lead it is through the clip 21, rod 18, link 20 and socket 18.

If any defects appear during factory tests, or if any develop while the terminal is in use afterwards, the joint between the sleeves 2 and 12 may be easily unsoldered and the sphere 7 with its sleeve 12 and the enclosed parts separated from the stem.

10 The defective part may then be repaired or it may be discarded and replaced by a new part, the part which is not defective being saved in either case. The construction of the terminal is also such that it may be

15 used in connection with an oil-filled transformer casing with practically no danger of leakage of oil through the terminal or around its base.

What I claim as new and desire to secure by Letters Patent of the United States, is,—

20 1. In a terminal for electrical apparatus, a tubular stem, a conducting sleeve enclosed in the stem, a conductor within the sleeve and insulated therefrom, the conducting sleeve and conductor being each arranged for connection with electrical apparatus at each end, and the conducting sleeve being secured to the stem near one end only,

25 30 whereby the conducting sleeve and con-

ductor may be removed from the stem by disconnecting it near one end.

2. In a terminal for electrical apparatus, a tubular stem including an outer insulating portion and a conducting sleeve moulded 35 into one end thereof, two conductors within said stem and insulated from each other, one of said conductors surrounding the other and being secured to said sleeve near the end of the stem only, and said two conductors being each arranged for connection with electrical apparatus at each end. 40

3. In a terminal for electrical apparatus, a tubular stem, a hollow conducting member fitting against one end of the stem, a 45 conducting sleeve extending from said hollow conducting member through the stem and secured to the stem at its opposite end only, and a conductor extending from the space within said hollow conducting member to the opposite end of said conducting sleeve and insulated from said member and sleeve, said hollow conducting member, the opposite end of said sleeve and each end of said conductor being arranged for connection with electrical apparatus. 50 55

In witness whereof, I have hereunto set my hand this 19th day of September, 1921.

EDWARD A. WAGNER.
